INVENTOR
C. W. G. Sodemann
BY
James L. Hopkins,
ATTORNEY

UNITED STATES PATENT OFFICE.

CHRISTIAN W. G. SODEMANN, OF ST. LOUIS, MISSOURI.

RADIATOR-SHIELD.

Specification of Letters Patent. Patented June 15, 1920.

1,343,414.

Application filed June 2, 1917. Serial No. 172,371.

To all whom it may concern:

Be it known that I, CHRISTIAN W. G. SODEMANN, a citizen of the United States, residing at the city of St. Louis and State of Missouri, have invented certain new and useful Improvements in Radiator-Shields, of which the following is a specification, reference being had therein to the accompanying drawing.

10 My invention relates to improvements in radiator shields, and has for its object to provide a dust deflecting and dust collecting shield for steam and hot water radiators, said shield having means for adjustment and detachable fastening with relation to the radiator, the shield having side brackets adapted to support a top-slab for ornamental and heating purposes, and the brackets having guide-elements to aid in shaping 20 the main body of the shield to the desired conformation.

In the drawings—

Figure 1 is a perspective view of a shield embodying my invention in place upon a radiator, the shield being provided with a top slab.

Fig. 2 is a similar view of the same, the slab being removed.

Fig. 3 is a vertical elevation of one of the 30 brackets employed in said shield.

Fig. 4 is a fragmental front elevation of one end of the shield.

Fig. 5 is an enlarged detail of the centering clamp employed in mounting said shield, the adjacent bracket being shown in section as on the line 5—5 of Fig. 3.

Fig. 6 is a sectional view of the edge of the mounting in the bracket 10 taken on the line 6—6 of Fig. 3.

40 As shown in the drawings the radiator 6 is of usual construction, and the shield consists of a main body section comprising the vertical back 7, the top 8 and the forwardly projecting lip 9. Side-brackets 10—10 have 45 an inwardly projecting rib 11 in the form of an inverted L, and similarly projecting lugs 12, the sheet of metal forming the body section being formed and mounted in place between the rib 11 and lugs 12 as 50 shown in Figs. 3 and 6.

Beneath the lip 9 and contacting therewith is the dust-collecting trough 13 extending across the front of the shield, from bracket 10 to bracket 10, and open at its back as shown in Fig. 3. The trough 13 is 55 hingedly mounted on the pintle 14, and has

a rearwardly projecting prong 15 which contacts with the outer end of the flat spring 16 to keep the trough 13 in normally closed position. A finger-catch 17 is depressed to 60 open the trough 13 and remove the accumulated dust.

Each bracket 10 has an upwardly projecting tooth 18 to engage with an indentation (not shown) on the lower face of the 65 slab 19 when it is desired to provide the shield with such a slab.

Each bracket 10 has an inwardly projecting foot 20 adapted to rest on top of the radiator (see Fig. 3) and a guide-rib 21, 70 whose lower end is flared as shown at 22 to guide the shield into proper contact with the edge of the clamp-bar 23 (see Fig. 5).

Said clamp-bar 23 has a series of indentations 24 on its inner face, at each side of 75 its central screw-seat 25, which indentations 24 engage with the rear edges of two of the radiator coils 26—26, and the bar 23 is held in place against said coils 26 by means of locking-plate 27 and screw 28 as 80 shown in Fig. 5. The clamping means thus described can be fitted to various sizes of radiator, and serves to support the vertical back wall 7 of the shield at a proper distance from the radiator 6 and in alinement 85 therewith.

The described mounting renders the shield readily removable from the radiator for purposes of cleaning and the like.

When the slab 19 is not to be employed, 90 the tooth 18 and rear corner 29 are removed from each of the brackets 10, leaving the structure shown in Fig. 2.

The screw-seat 25 divides the clamp-bar 23 into two arms of unequal length (see 95 Fig. 5), so that by reversing said bar 23 the bracket 10 may be held at a greater or less distance from the end of the radiator 6. The sheet of metal forming the back 7 is stretched over the projection 30, and (see 100 Fig. 5) forced backwardly from the coils 26, to prevent overheating of said back 7. By means of its described construction the clamp of my invention is designed to mount shields of various sizes upon the same radiator, or shields of the same size upon various lengths of radiators; a provision made 105 valuable because of the lack of standardization in the various makes of radiators.

When the structure of my invention is 110 mounted in place, as shown in Figs. 1 and 2, it is balanced with reference to the radi-

ator 6, and properly spaced apart therefrom by means of the feet 20 and the clamp-bars 23; so that there is a channel between the back 7 and the top 8, and the radiator 6 as indicated in Fig. 3 to guide the dust particles in the ascending heated air upwardly and forwardly to be caught in the trough 13.

Having thus described my invention, what I claim as new and desire to have secured to me by the grant of Letters Patent, is—

In a radiator shield, the combination of two side-brackets; a main body section mounted between said brackets and forming

a vertical wall, a top, and a forwardly projecting lip; a dust-collecting trough mounted beneath and contacting with said lip; a clamp arranged to be detachably mounted between two coils of a radiator and to engage and hold one of said brackets at a predetermined distance from the radiator; and an inwardly projecting foot carried by each of said brackets and arranged to rest on top of the radiator.

In testimony whereof I hereunto affix my signature.

CHRISTIAN W. G. SODEMANN.
